United States Patent Office.

JOHN HUGHES, OF BUCHANAN, PENNSYLVANIA.

Letters Patent No. 98,383, dated December 28, 1869.

IMPROVEMENT IN LANTERNS.

The Schedule referred to in these Letters Patent and making part of the same.

To all whom it may concern:

Be it known that I, JOHN HUGHES, of Buchanan, in the county of Allegheny, and State of Pennsylvania, have invented certain new and useful Improvements in Lanterns; and I do hereby declare that the following is a full, clear, and exact description thereof, reference being had to the accompanying drawings, making part of this specification, in which—

Figure 1 is an elevation of one side of my improved lantern, complete.

Figure 2 is a sectional view of the latch and its lock.

Figure 3 shows the latch unlocked, and drawn back from the base-ring of the guard.

Figure 4 is a perspective view of the latch, its lock, and a portion of the guard-ring.

Figure 5 is a sectional view of the top collar of the lantern, showing the strengthening-plates applied to it.

Figure 6 shows one of the strengthening-plates before it is bent.

Similar letters of reference indicate corresponding parts in the several figures.

The object of this invention is—

First, to improve a lantern, by providing its spring-latch with a pivoted locking-plate, which will allow this latch to be locked over the base of the guard-ring, so as not to be liable to casual displacement; and

Second, to employ narrow perforated strengthening-plates, for affording increased thickness and strength of metal at those points where the ends of the lantern-bail are connected to the collar or top of the lantern, all as will be hereinafter explained.

To enable others skilled in the art to understand my invention, I will describe its construction and operation.

In the accompanying drawings—

A represents the top section or collar of the lantern;

B, the bail, which is pivoted to it.

C is the wire guard, which connects the top and bottom sections of the lantern, and affords protection to the glass globe inside of it; and

C' is the base-ring of this guard, which is connected at one side to the base D, by means of a joint, and at the other side by means of a latch, E.

D is the flanged base of the lantern, containing the lamp, and having secured to it the spring-latch E and lock-support g.

By drawing back the upper end of the spring-latch E, as shown in fig. 3, so as to release the guard-ring C, the base can be moved about its hinged jointed connection, and the glass globe can be removed from the guard.

The spring-latch E is rigidly secured to the base D, exteriorly, and extended upward and outward to a proper height. This latch is then bent inwardly a short distance, and then upwardly and outwardly, as shown in the drawings, thereby forming a latch, which, when unrestrained, will spring over the guard-ring C', and hold the same in place on the top flange of the base D.

When it is desired to remove the globe from the lantern, the finger is applied to the lip or upper end e, of spring E, and this spring drawn outwardly, until its bend or shoulder releases the guard-ring C'. The two parts C and D may then be flexed about their joints, and the globe removed.

In such a lantern, it is very desirable to employ some means which will prevent the latch from being casually displaced, and, for this purpose, I secure to the top flange d, of base D, a loop or bearing, g, which embraces the spring-latch, and to which is pivoted a tongue, h, as shown in the drawings.

This tongue h is a flat plate, a little wider than the width of the latch, and of such length as will allow it, when in the position indicated in figs. 1, 2, and 4, to lock the latch E, and prevent this latch from being drawn back to release the guard-ring C'.

By having the tongue h wider than the latch E, this tongue can be easily moved out of locking-position to the position indicated in fig. 3.

The top A has a bail, B, pivoted to it, by which latter the lantern is carried about.

To strengthen the points of attachment of the bail to this top A, I employ oblong strips, a, having a central eye, a'.

These strips of metal are secured to the top A, diametrically opposite each other, at the points where it is desired to attach the ends of the bail, by cutting slits through said top, at proper distances apart, and inserting through these slits the ends of the said strips.

The ends of the strips are then bent and lapped, as shown in fig. 5, after which the ends of the bail B are passed through the strips, and through holes made through the top A.

The strips or strengthening-pieces may be applied from the outside or inside of the top A, and they may be applied vertically or horizontally.

It will be seen from the above description, that by means of a very simple attachment, g h, to the lantern, I am enabled to lock the latch E, so that it will not be liable to casual displacement, at the same time, by a simple manipulation, the tongue h can be turned back, and the latch moved, so as to release the guard-ring.

It will also be seen, that without the use of solder, which is liable to melt, I am enabled to thicken and

strengthen the top A at the points where the ends of the bail are attached to it, thereby preventing the metal of said top from tearing out, and allowing the bail to become detached.

Having described my invention,

What I claim as new, and desire to secure by Letters Patent, is—

1. The combination of a pivoted locking-tongue, h,

with a latch, E, applied to a lantern, substantially as described.

2. The application of perforated strengthening-strips a to the lantern-top, A, substantially as and for the purposes described.
